RECEIVER AND BOLT MECHANISM FOR FIREARMS

Original Filed Sept. 26, 1945

UNITED STATES PATENT OFFICE

2,567,198

RECEIVER AND BOLT MECHANISM FOR FIREARMS

John C. Garand, Springfield, Mass., assignor to the United States of America as represented by the Secretary of War

Original application September 26, 1945, Serial No. 618,805. Divided and this application March 19, 1947, Serial No. 735,589.

5 Claims. (Cl. 89—188)

(Granted under the act of March 3, 1883, as amended April 30, 1928; 370 O. G. 757)

1

The invention described herein may be manufactured and used by or for the Government for governmental purposes, without the payment to me of any royalty thereon.

This invention relates to an improved bolt and receiver construction for automatic firearms.

This application is a division of my application Serial No. 618,805, filed September 26, 1945 for Firearms, now Patent No. 2,505,760.

The usual receiver and bolt construction for automatic firearms is generally of complicated design and consequently is extremely difficult to machine to the exacting dimensions required. This is particularly true of the bolt camming surfaces and of the locking surfaces or shoulders within the receiver against which the locking lugs on the bolt cooperate to lock the bolt to the receiver prior to discharge of the cartridge.

Accordingly it is an object of this invention to provide a receiver and bolt of improved design thereby facilitating fabrication of such receiver.

Another object of this invention is to provide a splined liner for a receiver terminating in a shoulder to provide a locking surface for the locking lugs for the firearm bolt.

Still another object of this invention is to provide a firearm bolt having cooperating lugs thereon adapted to engage the splined liner of the receiver.

A further object of this invention is to provide an improved means whereby the bolt is rotated to its battery position.

The specific nature of the invention as well as other objects and advantages thereof will clearly appear from a description of a preferred embodiment as shown in the accompanying drawings in which:

Fig. 1 is a longitudinal sectional view of the firearms;

Fig. 2 is a side elevational view of the receiver;

Fig. 3 is a cross sectional view taken along the line 3—3 of Fig. 2;

Fig. 4 is a side elevational view of a firearm bolt;

Fig. 5 is a view similar to Fig. 4 but showing the bolt rotated 90 degrees;

Fig. 6 is a rear end view of the bolt shown in Figs. 4 and 5;

Fig. 7 is a side elevational view of the liner; and

Figure 8 is a side elevation of the splined end of the bolt, rotated approximately 72° clockwise from the position shown upon Figure 6.

The receiver assembly 1 comprises essentially a receiver 9, a magazine latch 30, a magazine latch

2

spring 32, a liner 43, a rear sight 50 mounted on top of receiver 9, an ejector 62, a cap 67 and a buffer disk 72.

The receiver 9, Fig. 1, is in the form of a generally cylindrical hollow member defining an axial bolt-way 10 and is provided with two downwardly depending lugs, a forward lug 11, and a rearward lug 12 through which are provided coaxial holes 13 and 14 respectively, parallel to the axis of bolt-way 10 for a purpose to appear later. In rear lug 12 is a counterbored threaded hole 16 extending obliquely upward, radial to bolt-way 10, from the left side.

An ejection slot 17 leads from bolt-way 10 downwardly toward the left between lugs 11 and 12. A magazine well 19 is provided in receiver 9 leading from bolt-way 10 upwardly toward the right, substantially opposite ejection slot 17, the receiver being extended around well 19 to form a wall 20. A crosswise undercut 21 is provided at the forward end of magazine well 19 and a longitudinal slot 23 is provided in a rearward portion 22 of wall 20. A magazine latch 30 is pivotally secured in slot 23 by a transversely located pin 31.

Five inwardly projecting splines 38, preferably of equal width, are provided in the rearward half of bolt-way 10 in receiver 9, similar to the construction described in my prior Patent 2,386,205 for Firearms.

These splines, as will be shown later are provided for cooperation with bolt 100, being rounded at the front corner for that purpose as shown at 39, and are equally spaced around the inside of the receiver 9. A slot 41 is provided extending through the wall of the receiver in alignment with holes 13 and 14 in lugs 11 and 12 and extending from the rear end of receiver 9 forward and opening into hole 14. This slot occupies the space between two of the splines, the width of slot 41 corresponding to the width of the space between the splines. A small notch 42 is provided in one side of slot 41 for a purpose to appear later.

A camming shoulder 44a is required in bolt-way 10 forward of splines 38 and facing rearward, that is, toward the splines to initiate the rotating of the bolt relative to the splines. In order to obviate the difficulty of machining such a cam surface in the receiver, a tubular liner 43 with the rear end formed to constitute shoulders 44a and 44b (Fig. 7) is provided for assembly within receiver 9, being suitably secured in fixed location therein by means of a set screw 45 through counterbored obliquely disposed threaded hole 16.

Shoulder 44a is rounded and is arranged to provide a camming action to bolt 100 in a manner to appear later. Shoulder 44b is square and serves as a supplementary stop to prevent excessive rotation of bolt 100 as will be shown later. Liner 43 is cut away as at 46 to match ejector slot 17 and as at 47 to match magazine well 19. In the assembled relation, edges 48 of magazine well-cut 47 in liner 43 serve as shoulders against which the magazine (not shown) is held for positioning.

The use of a liner for obtaining a camming shoulder within the bolt-way in the receiver, without involving the difficulties of making an interior radial shaving cut, provides obvious advantages in simplicity of manufacture.

A thread 66 is provided on the rear end of receiver 9 for assembling a cap 67. This cap is provided for holding a buffer disk 72 in location at the rear end of bolt-way 10 to serve as a stop for cushioning the recoil stroke of the bolt 100. On one side of cap 67 adjacent the open end is provided an oblique lug 68 and extending through such lug is a rounded, radially disposed slot 69 as shown in Fig. 1. A radial key-way 71 is provided across the forward face of lug 68 on cap 67, coinciding with the center of slot 69.

The barrel assembly 2 comprises a barrel 80 having threads 81 for assembling to receiver 9, a chamber 82, and a bore 83. Chamber 82 accommodates a cartridge 8 having a case 76. An enlarged front end bearing portion 84 is provided to serve as a bearing for a front sight 87 comprising a sleeve 88 and a vane 89, the vane being offset to the left with respect to the axis of barrel 80 in order to align with a rear sight 50. Sleeve 88 is assembled on bearing 84 and is secured in location by a dowel pin 90 provided for that purpose.

A second bearing portion 85 with a radial gas port 86 through the bottom thereof is provided somewhat to the rear of bearing 84. A sleeve member 95, integral with a gas piston 96, is mounted on bearing 85. An aperture 97, in alignment with gas port 86 extends from inside of gas piston sleeve 95 radially outwardly, thereby providing a continuous passage from the bore 83 of barrel 80 through gas piston 96.

The bolt assembly 3 consists of a bolt 100, an extractor 118, a firing pin 135, and a firing pin spring 140.

Bolt 100 is of generally cylindrical form and is provided with an axial firing pin aperture 101, terminating at its forward end in a firing pin orifice 102. The juncture of firing pin aperture 101 and firing pin orifice 102 constitutes a shoulder 103.

In the rearward portion of bolt 100 is a longitudinal slot 105 extending inwardly to intersect firing pin aperture 101. The rear portion of slot 105 is extended obliquely rearward to the right as at 106 forming at the rear an oblique cam surface 107 and at the forward end of slot extension 106 a cam surface 108. A left wall 112 of slot extension 106 serves as a stop as will be shown. A slight shoulder 109 is provided in cam surface 108, all for cooperation with other parts as will be shown. A radial vent hole 110 is provided through the wall of bolt 100, just rearward of shoulder 103 to permit escape of any gases passing through the firing pin orifice 102 as a result of a punctured primer.

In the forward end of bolt 100 is a circular recess 111 coaxial with firing pin orifice 102 for receiving the head of a cartridge 8 when in

engagement therewith. An extractor 118 is provided along one side of bolt 100.

Diametrically opposite extractor 118 in bolt 100 is an ejector clearance groove 125. This groove extends from the front end of bolt 100 rearward to about the middle of the bolt at which point it is extended sidewise to the left as at extension 126. This ejector clearance groove 125 and extension 126 provide clearance for ejector 62 when the bolt moves forward and rotates into the locked position.

On the rearward portion of bolt 100, five lugs 130a, 130b, 130c, 130d and 130e are provided for cooperation with splines 38 in receiver 9 in a manner similar to that described in my above referred to Patent No. 2,386,205 for Firearms. However, in accordance with this invention, lugs 130a and 130b are longer than the others, lug 130a being rounded at its forward end as at 131 and arranged to engage camming shoulder 44a on liner 43 in receiver 9 and thereby initiate rotation of bolt 100 toward the locked position as it reaches the end of the forward stroke. If, as a result of wear or for any other reason bolt 100 fails to stop its rotation in proper locking position, shoulder 44b is provided to serve as a supplementary stop by engaging lug 130b at the appropriate position. The rear corners 132 of bolt lugs 130 are rounded for a purpose to appear later.

A firing pin 135 of substantially cylindrical form is slidably contained within bolt 100 as shown in Fig. 1.

The operating rod unit 4 consists of an operating rod 145, a set screw 150, an actuator 152, an actuator spring 159, and a spring guide 160.

Operating rod 145 is expanded at the forward end to form a cup or gas cylinder 146. The rearward end of the operating rod comprises a socket 147 and an operating arm 148.

Actuator 152 is of generally cylindrical form and has an axially aligned cylindrical stud 153 at the forward end arranged for engagement in socket 147 of the operating rod 145, being secured therein by set screw 150. Actuator 152 is substantially hollow, an axially coincident hole 154 extending through the actuator from the rear end to a point near the forward end, actuator spring 159 being inserted in such hole. A lug 155 provided on the upper rear end of actuator 152 is arranged to be engaged in slot 105 and slot extension 106 in bolt 100, whereby the motion of actuator 152 is transmitted to bolt 100 as will be shown later. A shoulder 156, with a forwardly facing bevel 157, is provided on the underside of actuator 152 at the rear end thereof, the purpose of which will appear later. Flutes (not shown) are provided in actuator 152 for lightening purposes.

The actuator spring guide 160 in the form of a tubular member is surrounded by actuator spring 159. This guide has a collar 161 at its rear end and a radial lug 162, the collar 161 serving as a shoulder for engaging the rear end of actuator spring 159.

In assembly, actuator 152 is slidably contained within aligned holes 13 and 14 in lugs 11 and 12 respectively on receiver 9. Lug 155 on actuator 152 extends generally upward through slot 41 in receiver 9 and into slot 105 in bolt 100. By this means longitudinal motion of actuator 152 is transmitted to bolt 100. Operating rod 145 is assembled to axial stud 153 of actuator 152, gas cylinder 146 on its forward end slidably engaging gas piston 96 on barrel 80. Cap 67 is threadably

assembled with buffer disk 72 therein at the end of bolt-way 10 to the rear end of receiver 9 and with slot 69 in lug 68 in axial alignment with hole 154 in actuator 152. Actuator spring guide 163 is inserted in the rear end of actuator spring 159, the forward end of such spring being passed forwardly through slot 69 in lug 68 into hole 154 in actuator 152.

Guide 160 is now forced forwardly compressing spring 159 and telescoping into actuator 152 until lug 162 on guide 160 passes through slot 69 in lug 68 on cap 67. The guide is then rotated until lug 162 thereon has passed through notch 42 in receiver slot 41 and comes into alignment with radial key-way 71 in cap lug 68 whereupon guide 160 is allowed to retract, seating lug 162 on spring guide 160 in key-way 71 in lug 68 of cap 67. In this position actuator spring 159 is under considerable compression thereby maintaining actuator 152 under a positive forward stress at all times.

A trigger mechanism 5 consisting essentially of a trigger guard 164 having a trigger slot 169, a trigger 174 having a sear stop 176, a pawl 182, a safety 190, a sear 198 having a beveled shoulder 203, a sear spring 200, a plunger 214 and plunger spring 220 is provided to control the fire of the firearm. As such mechanism constitutes no part of this invention no further mention thereof will be made except as to describe the function thereof in cooperation with the actuator. Such trigger mechanism is mounted on the underside of receiver 9 as shown in Fig. 1.

The above described firearm is of the gas operated type, the gas being taken from the bore 83 of barrel 80 through gas port 86 into gas cylinder 146 on the end of operating rod 145, the gas pressure developed in the gas cylinder upon discharge of cartridge 8 forcing the operating rod 145 and the actuator 152 rearwardly. Lug 155 on the top of actuator 152 being engaged in slot 105 in bolt 100 moves rearwardly and engages rearward camming surface 101 in the bolt slot 105, thereby imparting an oblique thrust against the bolt, the thrust being rearward and counterclockwise. The lugs 130 on bolt 100 being in endwise engagement with splines 38 in the receiver 9 prevent rearward motion of the bolt. Bolt 100 being free to respond only to the counterclockwise rotary component of the force is therefore rotated in a counterclockwise direction until the lugs 130 on the bolt pass out of endwise engagement with splines 38 in the receiver. Lug 155 then engages the left wall 112 of slot extension 106, thereby stopping rotation of bolt 100 with splines 38 and lugs 130 in slideable relation and hence converting the motion of bolt 100 from the counterclockwise rotary movement to a rearward longitudinal movement. The rounding at 39 and 132 on splines 38 and lugs 130 respectively provides clearance for facilitating the above described translation of motion of bolt 100.

Bolt 100 now moves rearwardly, extractor 118 holding the cartridge case 76 in engagement in recess 111 in the head of the bolt and thereby withdrawing the case from chamber 82 of barrel 80. As the case 76 is moved rearward, it is engaged near the edge opposite extractor 118 by the ejector 62 and is thereby ejected through slot 17. Meanwhile bolt 100 has passed to the rear of magazine well 19 in receiver 9 allowing the lowest cartridge 8 in magazine (not shown) to be moved by the magazine follower (not shown) to the bottom position where it is engaged by the edge of bolt 100 on its return stroke

and carried forward into the chamber 82 of barrel 80.

As actuator 152 moves rearwardly, actuator spring 159 is subjected to additional compression; hence at the end of the rearward stroke spring 159 is under maximum compression. Therefore the full compressive force of the spring is exerted forwardly against actuator 152. This force causes the actuator to immediately return forwardly, lug 155 engaging shoulder 109 on forward camming surface 108 in bolt 100 and, splines 38 and lugs 130 being in sidewise engagement, the bolt cannot rotate but instead moves forward until the splines and lugs are disengaged and the rounded shoulder 131 on lug 130a on bolt 100 engages camming shoulder 44a in liner 43 thereby camming the bolt in a clockwise direction to disengage lug 155 from shoulder 109 onto camming surface 108 which thereby rotates the bolt into the fully locked position.

At this point bevel 157 on shoulder 156 on actuator 152 engages beveled shoulder 203 on sear 198, camming the sear downward, but sear stop 176 on trigger 174 engages the sear just to the rear of trigger slot 169 thereby preventing further downward motion and retaining shoulder 203 thereon in engagement with shoulder 156 on the actuator so that actuator 152 is stopped immediately after bolt 100 is locked in firing position, but while the bolt is still about one-half inch from the extreme forward position.

When trigger 174 is pulled back, sear stop 176 on the trigger is pivoted forward out of engagement with sear 198 into alignment with trigger slot 169 thereby permitting the sear to move downward under the camming force of actuator 152, which, being freed from engagement by the sear, moves forward under the thrust of actuator spring 159. Lug 155 on the actuator engages firing pin 135 driving it forward to strike the cartridge.

As soon as the cartridge 8 is fired, the gas pressure developed tends to force the cartridge case and bolt 100 rearwardly, but splines 38 in the receiver 9 and lugs 130 on bolt 100 being in endwise engagement, the bolt is thereby prevented from moving rearwardly. As soon as the bullet of cartridge 8 has passed gas port 86 in the barrel 80, gas escapes through the port 86 and aperture 97 into gas cylinder 146 on operating rod 145 driving the entire operating rod assembly rearward to repeat the cycle above described.

From the foregoing description it is readily apparent to those skilled in the art that there is here provided an improved firearm receiver and bolt whereby difficult and expensive machining operations are substantially eliminated resulting in greatly increased production and large savings in costs.

60 I claim:

1. In a firearm, the improvement comprising, a hollow receiver having a bolt-way therethrough, a cam shoulder within said bolt-way, said shoulder being generally helically disposed with respect to the axis of the bolt-way, a bolt reciprocably mounted in said bolt-way and having a rotated locked position at the forward end of its reciprocating motion, a projection on the bolt constructed and arranged to engage the cam shoulder at the forward end of the bolt's reciprocating motion, whereby the bolt is rotatably cammed toward its locked position, said bolt having a laterally disposed recess, said recess having a cam wall generally helical with respect to the 70 axis of the bolt, an actuator slidably mounted

in the firearm, and a lug on said actuator engaged in the recess in the bolt, said lug cooperating with the cam wall to complete the rotary motion of the bolt to its locked position.

2. In a firearm, the improvement comprising, a receiver having a bolt-way therethrough, a plurality of circumferentially spaced internal splines in said bolt-way, a cam shoulder within said bolt-way, said cam shoulder being generally helically disposed with respect to the axis of the bolt-way, a bolt reciprocably mounted within said bolt-way and having a rotated locked position at the forward end of its reciprocating motion, a plurality of circumferentially spaced external lugs on said bolt, said bolt lugs slidably cooperating with said receiver splines to maintain the bolt in fixed angular alignment in the receiver during its reciprocating motion, said bolt lugs and said receiver splines being constructed and arranged so that said bolt lugs pass out of sidewise engagement with said receiver splines at the forward end of the reciprocating motion, and a projection on said bolt, said projection being constructed and arranged to engage the cam shoulder in the bolt-way as said bolt lugs and receiver splines pass out of sidewise engagement to thereby initiate rotation of said bolt into locked position.

3. In a firearm, the improvement comprising, a receiver having a bolt-way therethrough, a plurality of circumferentially spaced internal splines in said bolt-way, a cam shoulder within said bolt-way, said shoulder being generally helically disposed with respect to the axis of the bolt-way, a bolt reciprocably mounted within said bolt-way and having a rotated locked position at the forward end of its reciprocating motion, and a plurality of circumferentially spaced external lugs on said bolt, said bolt lugs slidably cooperating with said receiver splines to maintain said bolt in fixed angular alignment in the receiver during its reciprocating motion, said bolt lugs and said receiver splines being constructed and arranged so that said bolt lugs pass out of sidewise engagement with said receiver splines at the forward end of the reciprocating motion of the bolt, one of said bolt lugs being constructed and arranged to engage the cam shoulder in the bolt-way to initiate rotation of said bolt into locked position at the forward end of the reciprocating motion of said bolt.

4. In a firearm, the improvement comprising, a receiver, a liner secured in coaxial relation within said receiver, said receiver and said liner together defining a bolt-way extending longitudinally therethrough, a cam shoulder formed on the rearward end of the liner, said cam shoulder being generally helically disposed with respect to the axis of the bolt-way, a plurality of circumferentially spaced internal splines in the bolt-way in the receiver, a bolt reciprocably mounted in the bolt-way and having a rotated locked position at the forward end of its reciprocating motion, and a plurality of circumferentially spaced external lugs on said bolt, said bolt

5 lugs slidably cooperating with said receiver splines to maintain the bolt in fixed angular alignment in the bolt-way during all but the extreme forward portion of its reciprocating motion, said bolt lugs being longitudinally disposed relative to said receiver splines so that at the forward end of the reciprocating movement of said bolt, said lugs pass out of sidewise engagement with said receiver splines, one of said bolt lugs being constructed and arranged to engage the cam shoulder on the liner to initiate rotation of said bolt toward locked position at the forward end of its reciprocating motion.

15 6 In a firearm, the improvement comprising, a receiver, a liner secured in coaxial relation within said receiver, said receiver and said liner together defining a bolt-way extending longitudinally therethrough, a cam shoulder on the rearward end of the liner, said cam shoulder being generally helically disposed with respect to the axis of the bolt-way, a plurality of circumferentially spaced internal splines in the bolt-way in the receiver, a bolt reciprocably mounted in the bolt-way and having a rotated locked position at the forward end of its reciprocating motion, a plurality of circumferentially spaced external lugs on said bolt, said bolt lugs slidably cooperating with said receiver splines to maintain said bolt in fixed angular alignment in the bolt-way during all but the extreme forward portion of its reciprocating motion, said bolt lugs and said receiver splines being constructed and arranged so that said bolt lugs pass out of sidewise engagement with said receiver splines at the forward end of the reciprocating motion of said bolt, one of said bolt lugs being constructed and arranged to engage the cam shoulder on the liner to initiate rotation of said bolt into locked position at the forward end of the reciprocating motion of the bolt, said bolt having a laterally disposed recess, said recess having a cam wall generally helically disposed with respect to the axis of said bolt, an actuator slidably mounted in the firearm, and a lug on said actuator engaged in said recess in said bolt, said lug cooperating with said cam wall to complete the rotary motion of said bolt to its locked position.
